UNITED STATES PATENT OFFICE.

ARTHUR J. LAING, OF DEARBORN, MICHIGAN.

CONDUIT BENDER.

Application filed January 24, 1927. Serial No. 163,058.

This invention aims to provide a simple, strong and effective means whereby a conduit may be bent, and, especially, bent in a vertical plane.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood 15 that changes in the precise embodiment of the invention herein disclosed, may be made within the scope of what is claimed, without departing from the spirit of the invention.

20 In the drawings:

Figure 1 shows in elevation, a device constructed in accordance with the invention;

Figure 2 is a top plan;

Figure 3 is a section on the line 3—3 of 25 Figure 1;

Figure 4 is a section on the line 4—4 of Figure 1.

The device forming the subject matter of this application preferably is made of metal 30 throughout, and includes a body 1 in the form of a plate. A U-shaped bracket 4 projects rearwardly from the body 1 at one end thereof, one side of the bracket being reinforced by an L-shaped buttress which is 35 joined to said side of the bracket, and to the body 1.

A clamping device 5, such as a set screw, is mounted in the bracket 4, and a support 40 6, such as a vertical post, may be engaged between the set screw 5 and the opposite side portion of the bracket. If no post 6 is available as a structural element in the building where the conduit-bending is being done, the operator can provide himself easily 45 with such a post. At its upper end, the body 1 or plate has a forwardly extended projection 7 which extends downwardly but part-way across the plate or body 1, the body 1 slanting downwardly from the projection 7, as shown in Figure 1. In the 50 lower edge of the projection 7 there is an inverted V-shaped seat 8 adapted to receive the correspondingly shaped end 9 of a die 10 that lies against the body 1, the die 10 having an arcuate lower edge 11 in which there is a groove 12. A securing element 14 of any

desired sort is mounted in the projection 7 and in the body, the securing element 14 extending across the seat 8 and through the end 9 of the die 10. The die 10 has a shoulder 15 which seats against the lower edge of the projection 7, as shown in Figure 3. Owing to the way in which the seat 8 and the end 9 of the die 10 cooperate, together with the further fact that the shoulder 15 is provided, practically all of the strain in the pipe-bending operation is taken off the securing element 14, the securing element 14, serving, primarily, merely to prevent the die 10 from dropping downwardly 65 out of the seat 8 in the projection 7.

Near to its lower end, the body 1 is supplied with a forwardly extended off-set 16, in the upper edge of which there is a V-shaped seat 17 adapted to receive the correspondingly shaped end 18 of a bracket 19 which lies against the body 1, the bracket 19 being provided in its upper end with a groove 20 which is complementary to the groove 12 of the die 10. A securing element 21 70 passes through the off-set 16 into the body 1 and extends through the end 18 of the bracket 19; but, as has been stated hereinbefore in connection with the securing element 14, there is little or no strain on the securing element 21, the said securing element merely retaining the end 18 of the bracket 19 engaged in the seat 17, against accidental displacement.

The numeral 22 designates a metal conduit adapted to be used by electricians and others, it being necessary, very often, to bend such a conduit. When the conduit is to be bent, one end of it is placed in the groove 20 of the bracket 19, and the conduit is engaged in the groove 12 of the die 10. A hook 23 or the like may be secured at 24 to the conduit 22 and then, by means of a block and falls (not shown) or any other suitable agency, the conduit 22 can be flexed into curved form along the base of the groove 12 in the die 10. The construction is such that the die 10 can be taken out and replaced by another die having a different curvature, if desired.

There are power benders on the market but, often, they are expensive, bulky, and dangerous to operate. Hand benders are difficult to operate, and to mount securely. Such benders, moreover, are often damaged if a heavy pipe is used. The device forming the subject matter of this application is

light, portable, and avoids the objections heretofore entered against either power benders or hand benders. The dies can be interchanged as desired, and the conduit is 5 always being bent in a vertical plane. The result is that the conduit, as it is being bent, may be viewed readily, and the bending can be carried on intelligently to any desired extent, or stopped at any point.

10 What is claimed is:—

In a pipe-bending device, a plate-like body provided at one end with a forwardly extended projection, and at its opposite end with a forwardly extended offset, there being 15 a seat in the lower surface of the projection, and there being a seat in the upper surface

of the offset, a die having a reduced end received in the seat of the projection, a bracket having a reduced end received in the seat of the offset, the bracket and the die being 20 spaced for engagement with a pipe during the bending thereof, and securing elements engaged with the reduced ends of the die and of the bracket, the aforesaid reduced ends forming shoulders which engage the projection and the offset respectively and take the strain off the securing elements during the pipe bending operation.

In testimony that I claim the foregoing as my own, I have hereto affixed my signature. 25

ARTHUR J. LAING.
